United States Patent Office

Des. 212,216
Patented Sept. 17, 1968

212,216

WHEEL COVER

Chester B. Bostick, R.F.D. 1, Allentown, Pa. 18102
and Larry B. Bostick, R.F.D. 1, Schnecksville, Pa.
18078

Filed Aug. 22, 1966, Ser. No. 3,555

Term of patent 14 years

(Cl. D14—30)

FIGURE 1 is a front elevational view of a wheel cover, showing our new design;

FIGURE 2 is a side elevational view;

FIGURE 3 is a sectional view taken generally along the plane indicated by the line 3—3 of FIGURE 1; and

FIGURE 4 is a perspective view.

We claim:

The ornamental design for a wheel cover, substantially as shown.
